TEMPERATURE CONTROL FOR ELECTRIC HEATING

Walther Richter, Whitefish Bay, Wis., assignor to
 A. O. Smith Corporation, Milwaukee, Wis., a
 corporation of New York

Application June 21, 1943, Serial No. 491,634

9 Claims. (Cl. 219—20)

This invention relates to temperature controls for electric heating, and more specifically to the type of control designed to cut off the supply of energy upon a given energy consumption as in the successive electric heating of like objects to a predetermined temperature.

In most electric heating operations the greatest variable factor encountered lies in the large fluctuations in voltage of the supply system employed, since the heating effect varies as the square of the voltage. A 10% rise in voltage will mean a 21% rise in heating effect for the same amount of time.

Assuming that the articles to be heated are of substantially uniform shape and mass and that a constant voltage input can be provided, it would be possible to employ a timer for cutting off the heating operation for each article upon the elapse of a predetermined time to effect a given heating of each article. However, with the wide fluctuations in voltage in most factories, it is impossible to obtain a satisfactory control of temperature for the articles by merely timing the successive heating operations. Furthermore, the ordinary variations in mass of the articles being heated result in different input requirements for the same.

One of the objects of the present invention is to provide a device for cutting off the heating current that functions to proportion the time of heating substantially inversely as the heating effect, i. e., inversely to the square of the voltage.

Another object of the invention is to provide such a timer with compensation at least partially for the variation in heat loss in the articles due to the variation in time of heating.

Another object is to more accurately control the heating operations to obtain a heating of successive articles to a predetermined like temperature.

The invention has been embodied in an apparatus for controlling the induction heating of bomb bodies for forging the same, and the accompanying drawing illustrates this embodiment.

In the drawing, the single figure is a diagrammatic showing of an induction furnace with its circuit and control mechanism and an article disposed in the furnace for heating.

The furnace may be of the general type illustrated, in which a magnetic frame or core 1 is disposed to receive a bomb body 2 or other article to be heated. The energizing or primary coils 3 are supplied with current from a suitable power transformer 4 which in turn receives current from the power station 5. The article 2 serves as the secondary of the induction furnace and has

currents induced therein which effect the heating of the article.

Since there are usually several furnaces supplied with power from the same station 5 and in addition, a large number of other power consuming devices in the same shop supplied from the same station, there is a wide fluctuation of voltage in the line. When the voltage is relatively high in any one furnace the heating is more rapid and, conversely, when the voltage is low the heating is less rapid. This rapidity of heating varies as the square of the voltage, other things remaining equal.

Likewise, the ordinary variations in size and mass of the article being heated result in different energy consumption for different articles at any given voltage.

In timing the heating of successive articles the voltage and mass is taken into account by employing a watt-hour meter 6 connected as shown in the drawing. The meter 6 is of ordinary construction having a revolving disc 7 rotated in response to the energy passing through the coils of the meter. For this purpose, the two lower current coils 8 disposed beneath the disc 7 and a central voltage coil 9 disposed above the disc 7 provide the motive power for driving the disc.

The coils 8 are connected in series in a line 10 containing a relatively high constant resistance 30 and connected across the lines 12 and 13 leading to the primary coils 3 of the induction furnace 1. A voltage divider having resistors 14 and 15 is connected across lines 12 and 13, and coil 9 is connected across the resistor 14.

If the resistors 14 and 15 of the voltage divider were constant or of constant ratio, the voltage applied to coil 9 would always bear a fixed ratio to the line voltage being supplied to primary coils 3 of the furnace. Hence both the voltage applied to coil 9 and the current flowing through coils 8 will vary as the line voltage varies and will effect driving of disc 7 at a speed corresponding to the square of the varying line voltage.

The rotation of disc 7 effects the opening of 45 cutout switch 16 in the line 13 supplying current to the coil 3 of the induction furnace. This is accomplished as shown by means of the gears 18 driven by disc 7 and in turn tripping a pilot switch 19 in an auxiliary control circuit 20 operating a solenoid 21 for controlling switch 16. Any other suitable means may be employed for operating switch 16 from the rotation of disc 7. A photoelectric counter responsive to the rotation of disc 7 has been employed.

The watt-hour meter connected as shown com-

penses for variations in voltage in the line supplying the induction furnace with energy, as described above. It also compensates within limits for the different energy requirements of different size workpieces. This latter compensation results from placing the current coils 8 in series with the fixed dummy resistance 11 so that the energy being measured and which determines the length of the heating cycle is that being consumed in the constant resistance 11.

Should a relatively large workpiece be subjected to heating, and assuming a constant voltage, the current input to the piece would be greater thereby tending to compensate for the size of the piece. A smaller workpiece would in turn have a higher resistance and result in less energy consumption over a given period of time, thereby compensating for its lower mass. By basing the operation of meter 6 upon the energy consumed by a dummy resistance, the time of heating is determined independent of the size of the workpiece. The variation in the heating time cycle results solely from the fluctuation of voltage in the line.

If the switch 16 were always operated to stop the supply of current to the furnace after a predetermined energy consumption registered by the meter 6, it is possible that a variable heating effect might result from the fact that the heat losses from the article 2 are determined principally by the time involved. Where the heating time is long, there is a greater total heat loss from the article than where the heating time is short. This means that when the heating current is shut off upon the consumption of a predetermined amount of electrical energy by the dummy resistance 11, the article may still have a different temperature than desired.

In order to more accurately control the temperature of the article and to compensate for variations in the heat loss, the voltage divider is constructed with automatically varying resistances. For this purpose, resistor 14 may be a non-linear resistance such as an incandescent lamp with a tungsten filament which increases in resistance as its temperature rises. An increased voltage across the voltage divider will then cause the voltage across the lamp to increase proportionally more than that across the total divider.

This means that where the line voltage feeding the furnace increases so that the rate of heating of article 2 goes up, making for less time for heat loss, the watt-hour meter will run faster than the normal proportion of the ratio of the square of the voltages, so that less energy will be supplied to the article. Where the line voltage decreases below the voltage known to give the correct heating of the article, the voltage across resistance 14 will decrease in a greater proportion than the total voltage, and the watt-hour meter will turn at a lesser speed than that proportionate to the square of the voltage and thereby supply the predetermined greater amount of energy to the article to compensate for the larger heat loss resulting from the longer time of heating.

The amount of compensation available can be increased by employing a non-linear resistance such as carbon filament incandescent lamps for resistor 15. Carbon filaments have a negative temperature coefficient and, therefore, would shift the voltage distribution even more to increase the proportion of voltage appearing across the resistor 14.

The amount of compensation available can be decreased by employing one or more smaller tungsten filament incandescent lamps in resistor 15 to counteract in part the compensation provided by resistor 14.

5 The temperature control of the present invention provides a relatively accurate means of determining the heating of the article, and it compensates for differences in size of the workpieces, 10 for the fluctuation of line voltage and for different heating time. The control can be applied in either electric induction or resistance heating.

15 Various embodiments may be employed within the scope of the claims.

I claim:

1. In a temperature control for electric induction and resistance heating operations, the combination with the work load and current supply lines of a heating system, a wattmeter having its voltage coil connected across the current supply lines and its current coils in series with a constant resistor also connected across the current supply lines in shunt to the work load, the connection of said voltage coil being made to a tap of a voltage divider bridging the supply line with a non-linear resistance in one element thereof to change the ratio between the voltage of said line and that applied to the coil of the meter so that the voltage will divide between the elements of the divider to give the voltage coil a higher proportionate voltage when the line voltage is high and a lower proportionate voltage when the line voltage is low to thereby compensate for different heat losses in the work and provide for the more nearly equal heating of each successive workpiece, and means responsive to the operation of said meter for stopping the heating cycle in a predetermined time as modified by voltage changes in the supply line and substantially by varying heat losses in the workpiece.

2. In a temperature control for electric induction and resistance heating operations, the combination with the work load and current supply lines of a heating system, a wattmeter having its voltage coil connected across the current supply lines and its current coils also connected across the current supply lines in shunt to the work load, the connection of said voltage coil being made to a tap of a voltage divider bridging the supply line with a non-linear resistance in one element thereof to change the ratio between the voltage of said line and that applied to the coil of the meter so that the voltage will divide between the elements of the divider to give the voltage coil a higher proportionate voltage when the line voltage is high and a lower proportionate voltage when the line voltage is low to thereby compensate for different heat losses in the work and provide for the more nearly equal heating of each successive workpiece, a constant resistor in series with the current coils of the meter to effect operation of the meter independent of the current passing through the work load and dependent upon the voltage supplied to the work load, and means responsive to the operation of said meter for stopping the heating cycle in a predetermined time as modified by voltage changes in the supply line and substantially by varying heat losses in the workpiece.

3. In a device of the class described having a working load, current supply lines, and a wattmeter with its voltage coil connected across one 75 element of a voltage divider shunting the work-

ing load, a tungsten filament incandescent lamp constituting at least part of the resistance of one branch of said voltage divider to modify the voltage applied to said meter so that the voltage will divide between the elements of the divider to give the voltage coil a higher proportionate voltage when the line voltage is high and a lower proportionate voltage when the line voltage is low.

4. In a device of the class described having a working load, current supply lines, and a wattmeter with its voltage coil connected across one element of a voltage divider shunting the working load, a tungsten filament incandescent lamp constituting a substantial part of the resistance of said element of said voltage divider to modify the voltage applied to said meter so that the voltage will divide between the elements of the divider to give the voltage coil a higher proportionate voltage when the line voltage is high and a lower proportionate voltage when the line voltage is low.

5. In a device of the class described having a working load, current supply lines, and a wattmeter with its voltage coil connected across one element of a voltage divider shunting the working load, a non-linear resistance constituting a substantial part of the resistance of one element of said voltage divider to modify the voltage applied to said meter so that the voltage will divide between the elements of the divider to give the voltage coil a higher proportionate voltage when the line voltage is high and a lower proportionate voltage when the line voltage is low.

6. In a device of the class described having a working load, current supply lines, and a wattmeter with its voltage coil connected across one element of a voltage divider shunting the working load, a carbon filament incandescent lamp constituting at least part of the resistance of the other element of said voltage divider to modify the voltage applied to said meter so that the voltage will divide between the elements of the divider to give the voltage coil a higher proportionate voltage when the line voltage is high and

45 a lower proportionate voltage when the line voltage is low.

7. In a device of the class described having a working load, current supply lines, and a wattmeter with its voltage coil connected across one element of a voltage divider shunting the working load, a substantial part of the resistance of said element having a positive temperature coefficient of electrical conductivity to modify the voltage applied to said voltage coil during the operation of said meter so that the voltage will divide between the elements of the divider to give the voltage coil a higher proportionate voltage when the line voltage is high and a lower proportionate voltage when the line voltage is low.

8. In a device of the class described having a working load, current supply lines, and a wattmeter with its voltage coil connected across one element of a voltage divider shunting the working load, a substantial part of the resistance of another element of the divider having a negative temperature coefficient of electrical conductivity to modify the voltage applied to said voltage coil during the operation of said meter so that the voltage will divide between the elements of the divider to give the voltage coil a higher proportionate voltage when the line voltage is high and a lower proportionate voltage when the line voltage is low.

30 9. In a device of the class described having a working load, current supply lines, and a wattmeter with its voltage coil connected across one element of a voltage divider shunting the working load, the employment of resistances in the

35 opposite elements of said voltage divider having different temperature coefficients of electrical conductivity to modify the voltage applied to said voltage coil during the operation of said meter, so that the voltage will divide between the elements of the divider to give the voltage coil a higher proportionate voltage when the line voltage is high and a lower proportionate voltage when the line voltage is low.
